Primary Examiner — Steven J Czyz*Assistant Examiner* — Varun Salil Kamat(74) *Attorney, Agent, or Firm* — Law Office Of Michael Chen; Che Yang Chen(57) **CLAIM**

The ornamental design for a base support for ball chair, as shown and described.

DESCRIPTION

FIG. 1 is a perspective view of base support for ball chair showing my new design;
 FIG. 2 is a front view thereof;
 FIG. 3 is a rear view thereof;
 FIG. 4 is a left end view thereof;
 FIG. 5 is a right end view thereof;
 FIG. 6 is a top view thereof;
 FIG. 7 is a bottom view thereof;
 FIG. 8 is a perspective view showing my new design arranged with a ball chair;
 FIG. 9 is a bottom perspective view thereof; and,
 FIG. 10 is a bottom perspective cross sectional view along the A-A line in FIG. 6.
 The broken lines depict environment that forms no part of the claimed design.

1 Claim, 6 Drawing Sheets(56)
